ANNUNCIATOR UNIT

Morris F. Ketay, Brooklyn, N. Y., assignor to
 Bendix Aviation Corporation, South Bend, Ind.,
 a corporation of Delaware

Application May 25, 1932, Serial No. 613,586

1 Claim. (Cl. 177—326)

This invention relates to electrical annunciators, and more particularly to annunciator panels and the mounting therefor.

One of the objects of the present invention is to provide a novel annunciator panel which represents a complete signaling unit and which is readily adapted to be added to or removed from a complex annunciator system, thus rendering it possible to increase or decrease the number of 10 signaling stations with utmost ease and facility.

Another object is to provide novel means for 15 wiring an electric annunciator panel whereby the same may be inserted into a complex annunciator system with but one additional connection being necessary.

The above and further objects and novel features of this invention will more fully appear from the following detailed description when taken in connection with the accompanying drawings. It is to be expressly understood, however, that the drawings are for the purpose of 20 illustration only and are not designed as a definition of the limits of the invention, reference primarily being had for this purpose to the appended claims.

In the drawings wherein like reference characters refer to like parts throughout the several views:

Fig. 1 is a side elevation view of an annunciator panel embodying the present invention;

Fig. 2 is a rear elevation view of the same;

Fig. 3 is a front elevation view;

Fig. 4 is a top plan view;

Fig. 5 is a front elevation view illustrating the 35 combination of a number of the panels forming a complex annunciator panel; and

Fig. 6 is a top plan view of Fig. 5.

One embodiment of the present invention has been illustrated in the drawings, by way of example, in the form of a novel annunciator panel wherein a signal at the panel is given by a gravity type annunciator drop which is also effective to close electrical circuits whereby other local or remote signals may be given. The panel, as shown, comprises a suitable supporting member or bracket 4 which is attached to a panel plate 5, and on which is mounted all apparatus necessary to make up a complete annunciator unit.

Signaling means are provided on the panel and, 50 as shown, such means are constituted by a gravity type annunciator drop, the specific construction of which, per se, constitutes no part of the present invention. The drop is mounted on bracket 4 by means of a second bracket 6 and is adapted 55 to be actuated by a coil 7. An armature 8 adapted

to be attracted to the core of coil 7 is pivoted near the lower end thereof as on the bent portions X and Y, and is normally held upright by means of a spring 9, the free end of which extends into a hole in the lower center portion Z of armature 8. A signal or indicating card 10, one end of which is normally supported by armature 8 in the position shown in Figs. 1 and 4, is so mounted on bracket 6 that it will fall forward, pivoting on the lower ends of arms 11 and 12, as the upper 10 end of said armature moves to the right when attracted by coil 7. The card 10 will then indicate to the observer, through a hole 13 in plate 5, the zone or station from which the signal was sent. Any suitable means (not shown) may be 15 provided for returning card 10 to its raised position.

If desired, suitable means may be provided for initiating other local or remote signals and, as illustrated, a pair of normally separated contacts 20 14 are provided for completing a suitable signaling circuit which may include such devices as buzzers, lights, bells, etc. Contacts 14 are shown suitably mounted on bracket 6 and are adapted to be closed, when card 10 drops to signaling 25 position, by an elbow 15 securely attached to, and pivoted with, arm 11.

Local automatic switching means may also be provided to meet with the requirements of the external signaling circuit and such means, as 30 shown, are constituted by a multi-contact relay coil 16 mounted on bracket 4. Two pairs of contacts 17 and 18 mounted on a frame structure 19 which is attached to coil 16 are adapted to be alternately opened and closed by armature 20 35 as said coil is energized and de-energized. The armature 20 is adapted to be rocked about the corner of frame 19 as a pivot by the magnetic attraction of coil 16 when the latter is energized, thereby opening contacts 17 and closing contacts 40 18 against the resilient effort of the center arms of said contacts which act as springs to normally hold the armature in the position shown in Fig. 1. A clip 21 which fits into an opening in armature 20 and is fastened to frame 19 by means of 45 a set screw is provided with lateral projections 22 which overlap said armature and pivotally hold the same in place. The number of contacts to be provided with coil 16 will depend upon the circuit requirements of the entire annunciator system 50 of which the panel forms a part.

Novel means are provided for electrically connecting a number of the panels comprehended by this invention into an annunciator system comprising a large number of stations, such means 55

being so constructed as to make the usual manual connections between adjacent panels unnecessary. In the form illustrated, the novel connecting means are constituted by a plurality of electrical conductors or bus bars 23 mounted, together with local terminals 24, between a pair of insulating plates 25 (Fig. 1) which are suitably attached to bracket 4 below the annunciation unit. The conductors 23 extend laterally from either side of bracket 4 and the projecting portions thereof are curved forwardly, thus presenting a large contacting surface for engagement with a like conductor on an adjacent panel. Preferably, bus bars 23 are resilient in character so that they will exert some pressure against each other, thereby assuring firm connections, but not a positive one, between adjacent panels as indicated in Fig. 6.

By reason of the above-described novel means for electrically connecting adjacent panels, the local wiring of each panel may be of a permanent, individual nature so that when a number of panels are assembled for forming an annunciation system, only one connecting wire need be brought to each panel. For this connection, an outlet terminal 26 is mounted at a suitable point on, and insulated from, bracket 4. The local circuit of each panel in a given system will depend upon the requirements of the remainder of the circuit.

If desired, a local control or test switch 27 may be provided in the local circuit. As shown, this switch is mounted on bracket 4 and has an actuating handle 28 mounted on the face of panel plate 5.

Three panel units are shown adjacently mounted in Figs. 5 and 6 illustrating how the same may be used to make up a unit serving a plurality of stations. Each panel may be mounted in place 40 on a suitable frame (not shown) by means such as screws through holes 29. Each unit, it will be noted, may be readily slipped out of place and another one quickly inserted.

A simple local wiring diagram is diagrammatically shown in Fig. 1 in order to illustrate one form that may be used on a panel of the type described above. The operation with the circuit shown is as follows: The plus and minus terminals of a suitable source of electrical energy (not shown) are connected to bus bars 23 (a and b). When the switch at the signaling station is closed, a circuit is closed from said source through the signaling station, terminal 26, coil 7, bus bar 23a and back to the source. Coil 7 is thereby energized, attracting armature 8 and permitting card 10 to drop to a position so that it is visible through hole 13. As card 10 drops, elbow 15 is effective to close contacts 14, completing a circuit from source through bus bar 23a, contacts 14, coil 16, bus bar 23b and back to source. Coil 16 being thus energized attracts armature 20,

opening contacts 17, closing contacts 18 and completing a circuit from source to a suitable signal (such as a bell, buzzer or light, not shown), bus bar 23c, contacts 18, bus bar 23a and back to source. The contacts 17, although not included in the circuit shown, may be used when a more complicated circuit is employed. Switch 27 may, among other uses, be connected in series with coil 16, thereby serving as a cut-out switch for the bell or buzzer signals.

There has thus been provided a novel annunciation panel which may be used for facilitating the expansion or reduction of large, complex annunciation systems such as power house annunciation systems, fire alarm annunciation, trouble signal annunciation, etc. Each panel may also be used as a complete signaling unit in itself. It will be noted that systems made of this type of uniform panels are also readily serviced since a spare panel may be quickly inserted for one which is out of order. Since only a single connection need be made when a change or an addition is made, it is not necessary to employ a skilled electrician for this purpose.

While there has been shown and described only one embodiment of the invention, it is to be expressly understood that the same is not limited thereto but may be embodied in various other forms. For example, any suitable signaling means may be provided in lieu of the gravity annunciator drop illustrated. Various other changes, other than that mentioned above, may also be made in the arrangement and design illustrated without departing from the spirit of the invention as will now be apparent to those skilled in the art. Reference will primarily be had, therefore, to the appended claim for a definition of the limits of the invention.

What is claimed is:

An annunciation unit comprising a cover plate 40 for mounting said unit on a frame with other similar units to form an annunciation panel of a complex annunciation system, a U-shaped mounting bracket having one bar thereof secured flat against the back of the cover plate and a bar 45 projecting perpendicularly therefrom to the rear thereof and carrying a third bar parallel with the first bar, a plurality of U-shaped bus bars mounted on said last named bar of said bracket extending parallel with the panel and spaced 50 rearwardly thereof, terminals for said bus bars, said bus bars projecting from said bracket to slidably contact similar bus bars of an adjacent unit upon insertion of the unit into position with said adjacent unit, and annunciation apparatus 55 located between said panel and said bus bars of a width approaching substantially that of the panel whereby such apparatus remains forward of said slidably contacting bus bars during the insertion of a panel.

MORRIS F. KETAY.
